UNITED STATES PATENT OFFICE.

LIPA POLINKOWSKY, OF LONDON, ENGLAND, ASSIGNOR TO WESTERN ELECTRIC COMPANY, INCORPORATED, OF NEW YORK, N. Y., A CORPORATION OF NEW YORK.

MACHINE-SWITCHING TELEPHONE-EXCHANGE SYSTEM.

1,345,879.

Specification of Letters Patent.

Patented July 6, 1920.

Application filed March 9, 1918. Serial No. 221,552.

To all whom it may concern:

Be it known that I, LIPA POLINKOWSKY, a citizen of Russia, residing at 70 Westbourne Terrace, Hyde Park, London, W., England, 5 have invented certain new and useful Improvements in Machine-Switching Telephone-Exchange Systems, of which the following is a full, clear, concise, and exact description.

10 This invention relates to machine switching telephone exchange systems, and more particularly to systems of this character adapted for use in connection with toll or junction-line switchboards wherein incoming calls from outside of the exchange are answered by an operator and the desired connection is established by such operator, special facilities being given for controlling the establishment of the connection and the 15 ringing of the desired subscriber.

20 A particular feature of the invention, therefore, involves arrangement of the circuits and apparatus so that the toll operator may with facility and accuracy establish the 25 desired connection in accordance with the well-known principles of modern toll operation.

One of the broader features of the invention relates to the interrelation between a 30 toll switching system utilizing machine switching to extend the call to the desired line and the usual or local machine switching exchange or network (either full automatic or semi-automatic) in which such desired line appears, whereby maximum efficiency is achieved while utilizing the minimum apparatus.

Another of these more specific features involves a special form of group selector 40 adapted to the special requirements of systems of this character.

Another particular feature of the invention, therefore, has to do with the correct and simple arrangement of the fundamental 45 or selection controlling circuit from the controlling equipment of the toll operator to the trunk over which the connection is to be extended through a plug and jack.

50 A further feature involves that both the insertion of the plug of a connecting circuit or cord to which the call has been extended into the jack of the trunk line over which it is to be further extended and the depression of such assignment key individual to such call is a necessary prerequisite

of the association of such equipment with such call thereby preventing false operation of the equipment and consequent loss of time due to the depression of the wrong assignment key.

60 Another feature of the invention has to do with the release of the operator's controlling equipment after the completion of the selection controlling operations for extending a given call, such release being controlled and produced after a proper interval by a set of relays forming a part of said equipment.

Another feature of the invention relates 70 to the provision in a system of the general character referred to of improved supervisory means especially adapted for a toll switching operator's position.

75 Still another feature of the invention relates to the restoration of the selection controlling counting relays to normal after a selection controlling operation and provides for an improved arrangement of circuits and apparatus whereby the cutting off of the current of such counting relays to restore 80 them is accomplished gradually rather than abruptly interrupted as heretofore.

85 A further feature of the invention provides means whereby the controlling equipment is prevented from being held out of service on account of the inability of the call to be extended, as for example by the inability of a trunk hunting switch to find an idle trunk. Such means in the embodiment shown when it has been brought into 90 association with a calling line as extended not only causes the controlling equipment to pass through its cycle of operations but also causes the signaling of the operator.

95 Another feature of the invention relates to the provision of circuits and apparatus whereby the extension of a call from a toll operator's position may take place over a two-wire or interoffice trunk while at the same time providing the special operating 100 features necessary and desirable in connection with a toll operator's position.

Another feature of the invention relates 105 to the arrangement of circuits and apparatus whereby premature disconnection may take place without tying up any of the apparatus involved or causing undue delay in the restoration of such apparatus to normal.

110 Still further features of the invention

will sufficiently appear from the description of the embodiment of the invention hereinafter described.

One embodiment of the invention is disclosed in the accompanying drawings in which:

Figures 1, 2, 3, 4, and 5 when taken together illustrate a complete toll operator's switching system for extending a call to a desired line;

Fig. 6 illustrates a two-wire or interoffice trunk leading from a toll operator's position and the modified apparatus utilized in connection therewith.

And Fig. 7 together with 7^a indicates diagrammatically a toll operator's machine switching system in its relation to a usual local exchange or network.

For the proper showing of the system disclosed in Figs. 1 to 5, inclusive, Fig. 2 should be placed under Fig. 1 and Fig. 3 under Fig. 2; whereas Fig. 4 should be placed to the right of Fig. 1 and Fig. 5 to the right of Fig. 4. To illustrate the system as embodying a two-wire or interoffice trunk from the toll operator's position, Fig. 6 should be substituted for Fig. 4.

Fig. 1 shows only so much of the connecting circuit or cord of the toll operator's position as is necessary for an understanding of the invention. Preferably the features shown in Fig. 1 would be embodied in what is known as a universal cord circuit which, however, as it is well known in the art, is not disclosed in detail. The set of counting relays 306 shown in Fig. 3 are precisely similar to counting relays as are well known in the art. The set of number keys shown is generally similar to those heretofore known and a sufficient description both of the counting relays and of the number keys will appear in the description of the operation of the system hereinafter given.

The group selector switches diagrammatically shown in Figs. 4 and 6 and also the final selector switch diagrammatically shown in Fig. 5 are well known in the art and details of these switches as such are therefore not necessary herein. Furthermore, the sequence switches indicated respectively at 451, 551 and 651 on Figs. 4, 5 and 6, respectively are precisely similar to those well-known in the art and will not be described in detail it being understood that the sequence switch contacts on the respective sheets of the drawings are individual to the sequence switches shown on the same sheet and are closed only in the positions indicated by the members adjacent to such sequence switch contacts. The exceptions are the contacts 452, 552 and 652, which are what are known as the local contacts of respective sequence switches and are open only in the positions indicated adjacent thereto.

The description of the system shown will best be given by a description of the operation thereof in connection with the extension of a call. It will be assumed that the toll operator has received a call over the 70 cord 101 indicated generally in Fig. 1. The operator thereupon inserts the plug 103 into the jack 104 of a trunk line leading to the group selector and its associated apparatus shown on Fig. 4. Having so inserted the 75 plug 103 she depresses the mechanically locking magnetically releasing assignment key 102 individual to this connecting circuit thereby establishing a circuit which may be traced from battery, through the slow 80 operating relay 202, left normal contact of the relay 201, conductor 251, contacts 108 and 106, of the key 102, sleeve of the plug 103, sleeve of the jack 104 and slow operating relay 401 to ground. This circuit causes 85 the energization of the relays 202 and 401. The energization of the relay 401 establishes a circuit over the sequence switch contact 453 top to drive the sequence switch 451 out of its normal position and such sequence switch will come to rest due to the closure of the sequence switch contact 452 only upon arriving in its fourth position, in which position such sequence switch will remain until the deenergization of the relay 95 401 as will be hereinafter described.

Meanwhile, the relay 202 by its energization has established a circuit through the lower normal contact of the wipeout key 203, from ground over the left contact and 100 armature of the relay 202, conductor 391 to the holding magnets 305 of the key set shown on Fig. 3. The energization of the relay 202 has also closed over its right contact and armature a circuit through the 105 progress lamp 205, back contact and right armature of the relay 207, back contact and right armature of the relay 208 for the equipment busy lamp 206, which lamp will be lighted so long as the equipment is busy. 110

The operator then depresses the number keys in accordance with the numerical designation of the desired line, that is, she depresses the appropriate thousands key 301, the appropriate hundreds key 302, the appropriate tens key 303 and the appropriate units key 304. It will be best understood that the numerical designation of the desired line is recorded in accordance with the decimal system of notation. In the embodiment of the invention as hereinafter described, translation takes place and is necessary in view of the fact that the final selector switches used are assumed to have access to 200 lines and the group selector 115 switches used are assumed to have access to approximately 200 trunks leading to final selector switches. The selection, therefore, takes place in accordance with some other system of notation than the decimal sys- 120 125 130

tem. This change from the decimal system to the non-decimal system is known in the art as translation.

If before the operator has depressed one key in each of the series of keys shown, she discovers that she has made a mistake, she may depress the wipeout key 203, which by opening the circuit through its lower normal contact causes the deenergization of the holding magnets 305 and the depressed keys are released. Then releasing the key 203 she may depress the proper keys in the respective key sets.

When the operator has depressed one key in each of the sets of keys 301, 302, 303, 304 that is, has completed the recording of the numerical designation of the desired line, a circuit is established from the lower normal contacts of the key 203, left armature of the relay 202, left armature and back contact of the relay 204, right winding of the relay 201, conductor 394, right contact of the depressed key 301, right contact of the depressed key 303, right contact of the depressed key 302, conductor 309 or 310, alternatively, left or right contact of the depressed key 304, depending on whether the circuit is extended through the conductor 309 or 310, through the back contact and armature of the lower counting relay of the pair of counting relays individual to the contact of the depressed key 304, through the upper relay of the pair of counting relays of such key to battery. This causes the energization of the relay 201 and of the upper counting relay referred to. The energization of the counting relay at this time is without effect as no circuit exists to ground over the conductor 399. The energization of the relay 201, however, has opened the circuit previously traced whereby the relays 202 and 401 were energized, and has closed a local locking circuit for its left winding over its left armature and front contact, the upper contacts of the key 203 and the back contact and armature of the relay 213, whereby the relay 202 is maintained energized after the relay 201 is locked up. The relay 401, however, is deenergized. The energization of the relay 201 has also closed a circuit over its right armature for the right winding of the relay 204 such circuit including the lower normal contacts of the key 203, and the left armature of the relay 202. The energization of the relay 204 has over its right armature prepared the fundamental or selection controlling circuit at the operator's equipment. By the attraction of its left armature it has opened the original energizing circuit for the relay 201 which, as will be recalled, included one of the counting relays, and while the relay 201 is maintained energized over its left winding the energized counting relay 65 is deenergized. The attraction of its arm-

ture, however, has closed at its front contact a circuit for the slow operating relays 210 and 211, which circuit includes the lower normal contacts of the key 203 and the left armature of the relay 202. The energization of the relays 210 and 211 prepares the locking up circuit for the various counting relays 306, so that the operator's equipment is now in condition to control the necessary selections for extending the call.

When the relay 401 was deenergized consequent upon the energization of the relay 201 as above described it closed a circuit over its armature and back contact and sequence switch contact 453 bottom to drive the sequence switch 451 out of its fourth position and into its sixth position. In the fifth and also sixth positions of the sequence switch 451 the fundamental or selection controlling circuit is completed at 85 the group selector and since it has been prepared in the operator's equipment may be traced from battery, through relay 402, sequence switch contact 464 bottom, ring contact of the jack 104, ring contact of the plug 80 103, contacts 113 and 114 of the key 102, conductor 252, conductor 397, back contact and armature of the cutoff relay 309, conductor 398, stepping relay 213, front contact and right armature of the relay 204, conductor 253 contacts 109 and 110 of the key 102, tip contact of the plug 103 and the jack 104, sequence switch contact 463 top to ground and back to battery. The closure of this circuit has caused the energization 100 of the relays 402 and the relay 213. The energization of the relay 402 closes a circuit for the tripping spindle power magnet 405 over the sequence switch contact 462 bottom and the tripping spindle thereupon operates 105 closing an intermittent circuit to ground over the top contact of the interrupter 422, and sequence switch contact 458 top to the fundamental circuit between the relay 402 and the sequence switch contact 464 bottom. 110 This intermittent circuit to ground, while it maintains the relay 402 energized, causes the intermittent deenergization of the stepping relay 213 in the well known manner.

Upon the original energization of the 115 stepping relay 213, the circuit for the relay 201 over its left winding is interrupted and such relay is deenergized, the relay 202, however not being deenergized since the original circuit therefor is reestablished including the left normal contact of the relay 201 and the relay 401.

The energization of the relay 213 has closed a circuit over its front contact, left armature and back contact of the relay 219, 120 left armature and back contact of the relay 218, left armature and back contact of the relay 217, conductor 395, left contact of the depressed thousands key 301, armature and back contact of the lower counting relay of 130

the pair of counting relays appropriate to such thousands key, winding of the upper counting relay of such pair to battery. This causes the energization of such upper counting relay which, by the attraction of its armature, prepares a circuit for the lower counting relay of such pair, which includes the conductor 399, back contact and armature of slow operating relay 212, and armature and front contact of the relay 211. The conductor 399 it might be here noted is also connected through the resistance 220 to ground through the front contact and armature of the relay 210. The lower counting relay of the pair referred to is not at this time energized, however, as it is shunted by the direct path to ground through its back contact and armature and the front contact and armature of the relay 213. The control of the movement of the tripping spindle of the group selector now takes place in the well known manner, that is to say, upon the first connection of the shunt circuit to ground through the top contact of the interrupter the relay 213 is deenergized removing the shunt from around the lower counting relay of the pair referred to causing the energization and locking up of such relay, such locking circuit including the upper counting relay of the pair, the lower counting relay of said pair, the armature of such upper counting relay and the conductor 399. The energization of such lower counting relay has extended a circuit from the left contact of the depressed thousands key 301 to the armature of the lower counting relay of the next pair to the left of the pair which has been locked up. Upon such subsequent energization and deenergization of the relay 213, an additional pair of counting relays will be locked up in the well-known manner, until as the tripping spindle of the group selector is about to move into the position necessary for the given selection, the relay 307 having at this time been energized, the relay 213 is again deenergized, whereupon the relays 309 and 308 are energized, the relay 309 opening the fundamental circuit at its back contact and thereupon causing, when the tripping spindle has moved into its next stopping position, the deenergization of the relay 402. The energization of the relay 308 closes a circuit over its front contact including the conductor 396, slow operating low resistance relay 212, back contact and armature of the relay 217, winding of the relay 207 to battery. The relays 212 and 207 are energized. The energization of the relay 212 opens the direct circuit to ground from the conductor 399 and reduces the amount of current by which the locked up counting relays are maintained energized. It also establishes a direct circuit to ground in shunt of the relay 210 and such relay, slowly retracting its

armatures, after an interval, opens the direct circuit from the conductor 399 thereby cutting off the current by which the counting relays remain locked up, and causing such counting relays to return to their normal condition. It will be observed that the relays 207 and 217, 208 and 218, 209 and 219 form a set of counting relays analogous to the counting relays 306. These relays cause the change over of the control of the counting relays 306 from one set or combination of the number keys to another set or combination thereof. When the relay 207 was energized it prepared a circuit for the relay 217 but such relay was not energized at that time because it was shunted by the low resistance path to ground over the conductor 396 and the front contact and armature of the relay 308.

While this first selection controlling operation has been going on the thousands progress lamp 205 has been lighted. The energization of the relay 207 at the conclusion of the thousands selection controlling operation has caused the extinguishment of such lamp 205 and the lighting of the hundreds progress lamp 220.

After the timed interval controlled by the relays 212 and 210, the counting relays have been restored to normal the relay 308 is deenergized, and the shunt being removed from around the relay 217, such relay attracts its armature and the circuits at the operator's equipment are now prepared, (the relay 309 having also been deenergized) for the next or hundreds selection controlling equipment.

Upon the deenergization of the relay 402 and the stopping of the tripping spindle in the desired position in the well known manner, the sequence switch 451 was driven out of the sixth position by a circuit including the back contact and armature of the relay 402, back contact and armature of the relay 407 and the sequence switch contact 461. Before this sequence switch 451 reached its ninth position, the operation hereinbefore described in the operator's equipment whereby such equipment is prepared for the hundreds selection controlling operation has taken place and the fundamental circuit will be again closed, energizing the relay 402. A second selection takes place in this group selector in the ninth position of the sequence switch 451.

In view of the fact that the service to be established over the toll operator's position is of special character and of limited amount, it is necessary and desirable that the amount of switching mechanism utilized should be reduced as far as possible. In accordance with this feature of the invention, therefore, the group selector shown on Fig. 4 is arranged to select, first a large group and then a smaller group in such

large group, both of such selections taking place under the control of the operator's equipment and finally, to select an idle trunk line in such smaller group. As shown, the 5 smaller groups referred to comprise only three trunk lines, each leading to final selector switches having access to the same lines. The group selector, therefore, has access to fifty groups, each bank or level of such 10 group (there being ten banks or levels) comprising five groups of three trunk lines and the busy back contacts individual to each such sub-group. It will be understood of course that the number of trunk lines in 15 each sub-group and the number of sub-groups in each bank or level may be altered as occasion or the traffic of the exchange may require. Also the switches utilized may have a capacity greater or less than 20 200 lines.

Upon the establishment of the fundamental circuit and the consequent energization of the relays 402 and 213, the relay 402 closes in the ninth position of the sequence 25 switch a circuit over the sequence switch contact 455 for the switch carriage power magnet 403 and the switch carriage therefore is set in motion causing the intermittent connection to ground from the fundamental circuit over the sequence switch contact 458 top and the upper contact of the interrupter 421 in the well known manner. This causes the intermittent energization and deenergization of the relay 213 in the 30 manner well understood and the consequent locking up of the various pair of the counting relays 306, beginning with the pair of counting relays connected to the left contact of the depressed hundred key 302. As 35 the final selector switches have a capacity of 290 lines the left contacts of the keys 302 are connected in pairs and as the various sets of trunk lines on the selected bank or level of the group selector comprise with 40 busy back contacts four sets of terminals, the respective pairs of keys 302 are connected with the first or number naught, the fifth or number four, the ninth or number eight, the thirteenth or number twelve, the 45 seventeenth or number sixteen pair of counting relays. If the hundreds key depressed was the first or second key, that is the number naught or number one key, the group selector switch carriage will take one step 50 under the control of the counting relays before the fundamental circuit is opened by such counting relays in the well known manner, causing the deenergization of the relay 402. If the third or fourth hundreds key, 55 that is the number two or three key, has been depressed, the group selector switch carriage will take five steps before the deenergization of the relay 402 by the opening of the fundamental circuit, and so on. 60 65 When, therefore, the group selector switch

carriage has taken the requisite number of steps to bring its brushes 408, 409 and 410 on the first set of contacts of the selected sub-group, the relay 402 is deenergized, opening the circuit for the power magnet 70 403 and causing the switch carriage to stop in the well-known manner, the holding relay 404 being energized over a circuit including the sequence switch contact 457, sequence switch contact 461 bottom, back contact and 75 armature of the relay 407 and back contact and armature of the relay 402. The deenergization of the relay 402 has also caused the sequence switch 451 to move out of its ninth position by a circuit including the 80 back contact and armature of the relay 407 and the sequence switch contact 461 bottom. In the tenth position of the sequence switch 451 the circuit through the left winding of the test relay 406 is closed through the sequence switch contact 459. If the first 85 trunk of the selected group of trunks is idle full battery potential will exist on the test conductor thereof through the relay 501 and alternatively the sequence switch contact 90 571 and the resistance 519. This will cause the energization of the relay 406 which by attracting its armature closes a low resistance path through its right winding, its front contact and armature, the relay 407 and sequence switch contact 456. This low resistance path so reduces the potential upon the test terminal of the selected 95 trunk line that no other group selector will be able to seize such trunk line. This method 100 of testing and guarding the selected trunk line, since it is well known in the art, need not be further described. The relay 407 is now energized and drives the sequence switch 451 out of its tenth position by a circuit 105 including the sequence switch contact 461 top and the back contact and armature of the relay 402. It will be noted that the fundamental circuit is entirely open at the group selector in the tenth and eleventh 110 positions of the sequence switch 451, the sequence switch contacts 463 and 464 having been opened as the sequence switch left its ninth position. The eleventh position of the sequence switch 451 is provided also as a 115 testing position but the provision of two testing positions is already well known in the art, the relay 407 when permanently energized, as has been described, driving the sequence switch 451 into its twelfth position. 120

If when the sequence switch came into its tenth position and the brushes 408, 409 and 410 were resting on the terminals of the first trunk line and the sub-group of such 125 trunk lines sufficient current would not appear upon the test terminal thereof to energize the relay 406 over its left winding, the relay 407 would, therefore, not be energized and a circuit would be established 130

for the power magnet 403 over the sequence switch contact 455 bottom, back contact and armature of the relay 407 and back contact and armature of the relay 402 to cause the further movement of the brush carriage until an idle trunk line is found, when, owing to the energization of the relay 406 and the relay 407, as has been hereinbefore described, the movement of the brush carriage is stopped and the idle trunk line is seized in the usual manner.

When upon the termination of the hundreds selection the relay 308 was energized, it closed a circuit over its armature and front contact, conductor 396, relay 212, right armature and front contact of relay 217, right armature and back contact of relay 218, winding of relay 208 to battery. The relays 212 and 208 are thereupon energized. The energization of the relay 212 causes the restoration of the locked up counting relays to normal in the manner hereinbefore described. The energization of the relay 208, by the movement of its right armature has caused the extinguishment of the hundreds progress lamp 220, and the lighting of the tens progress lamp 221. It has also prepared the circuit of the relay 218 which is energized when the relay 308 deenergized, due to the operation of the slow acting relays 212 and 210. The circuits are now prepared at the operator's equipment for the tens selection controlling operation.

When upon the seizure of an idle trunk line by the group selector the sequence switch 451 is driven into its twelfth position, the fundamental circuit is extended from the sequence switch contact 463 bottom over the brush 408 and the sequence switch contact 554 top to ground, and from the sequence switch contact 464 top, over the brush 409 and over the sequence switch contact 553 and the relay 502 to battery. The establishment of the fundamental circuit in this manner causes the energization of the relays 502 and 213, and tens selection now takes place in the final selector under the control of the counting relays 306 in accordance with the depressed tens key 303. Relay 502 on energizing drives the sequence switch 551 out of its first position over a circuit including the sequence switch contact 556. In the second position of the sequence switch a tripping spindle power magnet 505 is energized over the sequence switch contact 558 and front contact and armature of the relay 502. The tripping spindle, is, therefore, set in motion and the interrupter thereof 522 intermittently shunts the stepping relay 213 over a circuit including the sequence switch contact 559 top. As the tripping spindle is coming into its proper position, the fundamental circuit is opened in the well known manner by the energization of the relay 309 and the relay 502

is deenergized stopping the tripping spindle in its proper position and driving the sequence switch 551 out of its second into its fifth position over a circuit including the sequence switch contact 557 top. In the 70 fifth position of the sequence switch 551 units selection takes place, the fundamental circuit having meanwhile been established at the operator's equipment, the relay 209, 212 and 219 being energized in precisely the 75 manner in which the relays 208, 212 and 218 were energized as previously described. It should be noted that the energization of the relay 209 has caused the extinguishment of the tens progress lamp 221 and the lighting 80 of the units progress lamp 222. Relay 502 being again energized there is closed in the fifth position of the sequence switch 551 a circuit for the brush carriage power magnet 503 including sequence switch contact 561 85 bottom and the front contact and armature of the relay 502. The brush carriage thereupon moves causing the intermittent operation of the interrupter 521 and the intermittent energization of the relay 213 by the 90 closure of the shunt including the sequence switch contact 559 top and the top contact of the interrupter.

Depending on the number of the desired line it may be that it will be necessary for the final selector to take twenty steps to reach such desired line. It will be observed that the control of the counting relays in the units selection is determined both by the depression of the units key 304 and the hundreds key 302. If the hundreds digit is even it will only be necessary for the final selector to take ten or less steps to reach the desired line with the given units digit, whereas if the hundreds digit of the desired line is odd it will require from eleven to twenty steps for such final selector to reach the desired line of such units digit. The circuits of Fig. 3 obviously disclose the method of translation for producing this result. The circuit for the first pair of counting relays to be energized in this selection controlling operation may be traced, assuming the hundreds digit is even, from the armature and front contact of the relay 213 through the 100 conductor 394, right contact of the depressed thousands key 301, right contact of the depressed tens key 303, right contact of the depressed even hundreds key 302, conductor 309 and the left contact of the depressed units key 304. On the other hand, if the depressed hundreds key was odd this circuit would include instead of the conductor 309 and the left contact of the key 304, the 110 conductor 310 and the right contact of the key 304. The 115

Subject to this novel arrangement for translation in the number keys then the selection of the desired line by the final selec- 120

130

tor takes place generally in the usual manner. When the brushes 508, 509, 510 of the final selector are coming into contact with the terminals 511, 512, 513 of the desired line, the operation of the relay 309 of the counting relays causes the opening of the fundamental circuit and the consequent de-energization of the relay 502. The de-energization of this relay opens the circuit hereinbefore traced to the power magnet 503 and closes the circuit for the holding magnet 504 over the sequence switch contact 563 and the sequence switch contact 557 top. It also causes the movement of the sequence switch contact 551 out of its fifth position. Positions six and seven of the sequence 551 are reserved for private branch exchange trunk hunting but since private branch exchange trunk hunting forms no part of the present invention the sequence switch contact 560 is provided and the sequence switch 551 continues in motion until it comes to rest in its tenth position. In passing through its eighth position the sequence switch contact 564 is closed and the calling line is tested in the usual manner. If the desired line is idle the relays 506 and 507 are energized placing a busy guard upon the test terminal 513 of the desired line by reducing the potential normally applied to such terminal through the cut-off relay 517 of such line and the sequence switch 551 is driven directly through its tenth and eleventh positions into its twelfth position by a circuit including the armature and front contact of the relay 507 and the sequence switch contact 566. In the twelfth position of the sequence switch 551 a circuit is established for the relay 514 from the 24 volt battery through the relay 514, sequence switch contact 555 bottom, brush 409 of the group selector, the sequence switch contact 464 top, ring contact of the jack 104 and the plug 103, contacts 113, 112 of the key 102, which has meanwhile been released as will be hereinafter described, lower normal contact of the ringing key 124, and right winding of the relay 122 of 48 volt battery and ground. Relay 514 due to the relation of the two batteries in the circuit traced will be energized and by attracting its right armature opens the normally ringing circuit at such final selector, preventing the impression of ringing current on the desired line in the twelfth position of the sequence switch 551. By the attraction of its left armature the relay 514 drives the sequence switch 551 out of its twelfth position over a circuit including sequence switch contact 570, and the sequence switch 551 moves into its thirteenth position which is the talking position of this sequence switch, and the sequence switch contacts 568 top and 569 bottom now being closed a complete circuit is established from the cord circuit 65 101 to the desired subscriber sub-station.

The ringing of such sub-station will now take place at the will of the operator by the depression of the ringing key 124.

Before describing the ringing of the called subscriber the operations which take place 70 in the operator's equipment upon the completion of the units selection controlling operation will be described. Upon the energization of the relay 308 at the end of the units selection controlling operation a circuit 75 was established over armature and front contact of such relay, conductor 396, relay 212, right armature and front contact of relay 217, right armature and front contact of the relay 218 right armature and 80 front contact of the relay 219 and 214 to battery. This causes the energization of the relays 214 and 212.

The energization of the relay 212 restores the counting relays 306 to normal in the 85 well understood manner. The energization of the relay 214 causes the energization of the relay 215, said relay 215 by its energization establishing a locking circuit for the relays 212 and 214 over its left armature. 90 At the time when the relay 212 was energized the shunt through the front contact and armature of such relay and the front contact and armature of the relay 211 was closed around the relay 210 as hereinbefore 95 described and such relay, slowly falling off, not only has caused the restoration to normal of the counting relays, but on reaching its back contact has closed a circuit, after a proper timing interval, including the front 10 contact and right armature of the relay 214, front contact and right armature of the relay 215, conductor 254, contacts 115, 116 of the key 102 and right winding of the relay 117 causing such relay to energize. 10 The energization of the relay 117 closes a circuit by the attraction of its left armature for the releasing magnet 120 of the mechanically locking assignment key 102, the circuit for which includes as well the right 11 armature and the normal contact of the relay 121, and the relay 401. The key 102 is thereupon restored to its normal condition and the circuits as hereinbefore traced over the conductors 251 and 254 are interrupted 11 at the contacts 106, 108 and 115, 116 hereinbefore referred to. By the interruption of the circuit over the conductor 251 the relay 202 is de-energized disconnecting the holding circuits for the relays 207, 208, 209, 217, 12 218 and 219 by the retraction of its right armature and the holding circuit for the relay 204 by the retraction of its left armature. The relays 204, 207, 208, 209, 217, 218 and 219 are, therefore, restored to normal condition, the relay 219 opening by the retraction of its right armature the circuit of the relay 214, which by its de-energization opens the circuit of the relay 215. The de-energization of the relay 215 and the relays 13

217, 218, 219 have interrupted the circuit of the relay 212 and the deenergization of the relay 204 has interrupted the circuit of the relays 210, 211. Furthermore, the fundamental circuit is now open both at the key 102 and at the right armature of the relay 204. The retraction of the left armature of the relay 202 has also opened the circuit for the number key holding magnets 305 and the depressed keys are released.

All the apparatus, therefore, in the operator's controlling equipment shown in Figs. 2 and 3 has now been restored to normal.

This release of the equipment and the opening of the fundamental circuit is timed, however, by the slow operating relays referred to so that it will not take place prematurely and by the premature substitution of the circuit extending to the repeating coil of the cord circuit 101 for the portion of the fundamental circuit extending to the operator's equipment, cause a false operation on the final selector, while on the other hand such release will take place before the sequence switch 551 has in any event reached its tenth position. When the sequence switch 551 arrived in its eighth position the sequence switch contacts 554 bottom and 555 top are closed including between the two talking branches of the circuit, as extended to the final selector, the resistance 518. Upon the release of the key 102, therefore, a circuit is established to energize the supervisory relay 122, which operates and completes an alternative path for current from battery and the left locking winding of the relay 117 which is now energized, over the left winding of the relay 121, front contact and armature of the relay 122, contacts 107 and 108 of the key 102, sleeve contact of the plug 103 and jack 104, through relay 401 to ground. The resistances of the various windings and the resistance connected to the armature of the relay 122 are so adjusted that upon the closure of this circuit, the relay 121 is energized and the releasing magnet 120 is deenergized.

If the desired line has been found busy in the eighth or testing position of the sequence switch 551, such sequence switch would not move out of its tenth position and the relay 122, being maintained energized, the relay 117 is also maintained energized and the lamp 118 is connected in circuit with the interrupter 119 over the front contact and right armature of the relay 117, and by its consequent flashing indicates to the operator that the desired line is busy. If, however, as has been assumed, the desired line was found idle, the sequence switch 551 has moved into the thirteenth position thereof. On leaving its eleventh position the bridge through the resistance 518 is opened and in leaving its

twelfth position the circuit through the relay 514 is opened. When, as a result of one or both of these operations the relay 122 is deenergized, the relay 117 deenergized and the lamp 118 is continuously lighted to indicate that the ringing thereof may take place when desired. It should be noted that in order to avoid the unnecessary energization of the release magnet 120, the right armature of the relay 121 is arranged to release more slowly than the left armature of the relay 117.

The operator when she is ready to complete the connection depresses the ringing key 124. By the closure of the contacts 126 thereof a circuit is provided for the right winding of the relay 121 which by its energization closes a circuit from the source of ringing current 125, armature and front contact of the relay 121, lower contacts of the key 124, contacts 112, 113 of the key 102, ring contact of the plug 103 and jack 104, sequence switch contact 464 top, brush 409, sequence switch contact 569 bottom, brush 509, terminal 512, over the subscriber's line, and the ringer at the sub-station thereof, and back over the terminal 511, brush 508, sequence switch contact 568 top, brush 408, sequence switch contact 463 bottom, tip contact of the jack 104 and plug 103, contacts 110, 111 of the key 102 and upper contact of the key 124 to ground.

When the desired subscriber responds the circuit will be established during the usual intervals between ringing, that is, while the key 124 is not depressed to energize the supervisory relay 122, such circuit being precisely the ringing circuit traced except that it includes the normal contacts of the key 124, and right hand side of the repeating coil in the cord 101 and the windings of the relay 122. The energization of the supervisory relay 122 opens the circuit for the supervisory lamp 118 causing the extinguishment thereof since at this time relay 117 is not energized. Conversation will now take place between the operator and the desired subscriber and the desired subscriber and the distant subscriber whose call has been received by the toll operator upon the cord 101. The supervision on the operator's position takes place in the usual manner, the supervisory relay 123 on the calling end of the cord 101 being shown of the type which may be energized by either alternating or direct current to display the signal associated therewith, the supervision on the called side being of the type usual in any common battery exchange, that is the lamp 118 being lighted upon the deenergization thereof, such relay 122 being energized whenever the loop circuit to the desired subscriber's substantion is closed and deenergized whenever such circuit is open.

On the hanging up of the desired sub-

scriber's receiver the operator may cause the breaking down of the established connection at any time by the withdrawal of the plug 103 from the jack 104. This causes the de- 5 energization of the relay 401 which drives the sequence switch 451 out of its twelfth position over a circuit including the sequence switch contacts 453 bottom and such sequence switch moves into its sixteenth position. Since the sequence switch 551 has 10 passed out of its sixth position and the sequence switch contact 571 is open the relay 407 is deenergized at this time (the relays 501 and 406 are still energized) and since the 15 sequence switch has not yet reached its fourteenth position no circuit exists for the relay 402 and the sequence switch 451 is driven into its eighteenth position by a circuit including the back contacts of the relays 402 20 and 407 and the sequence switch contact 461 bottom. In the eighteenth position the restoration of the brush carriage takes place in the usual manner, which being completed, the sequence switch 451 is driven into its 25 first or normal position where the tripping spindle 405 is restored to its normal position in the usual manner. Since the restoration of the brush carriage and tripping spindle in systems of this character is well 30 known in the art they will not be described herein.

As the sequence switch 451 moved out of its sixteenth position the sequence switch contacts 459 and 456 being opened, the restoration of the final selector apparatus is 35 initiated by the deenergization of the relay 501. The retraction of the armature of such relay opens the original circuits of the relays 506 and 507, freeing the line of the 40 called subscriber and closes at its back contact the circuit over the sequence switch contact 557 bottom to drive the sequence switch 551 into its fifteenth position. Since the desired subscriber has restored the receiver to 45 its switchhook no circuit will exist in the fifteenth position of the sequence switch 551 for the relay 502 and the sequence switch will be driven over a circuit including the back contact of such relay and the sequence 50 switch contact 557 top into its sixteenth position from which position it will be driven by a circuit including the back contact and armature of the relay 501 and the sequence switch contact 557. In leaving its fifteenth 55 position the sequence switch 551 opened the contacts 564 and 565 which since the relay 501 is deenergized opens the circuits of the relays 506 and 507 and frees the called subscriber's line. In the seventeenth position 60 of the sequence switch 551 a circuit is again established therefor over the back contact and armature of the relay 502 and the sequence switch contact 557 top, (since the circuit over the sequence switch contact 553 65 is open at the group selector and at the jack

individual thereto) and the sequence switch 551 moves into its eighteenth position in which position the brush carriage is restored to and stops in its normal position in the usual manner. The tripping spindle has 70 been restored or may be now restoring since such restoration can take place in any of the positions of the sequence switch 551 from the twelfth to the first or normal position thereof.

All of the apparatus has now been restored to its normal condition and subsequent calls may be established thereover as desired. It should be noted that so long as the sequence switch 451 is out of its 80 normal position, that is, so long as the apparatus of the group selector is not ready to be used in the establishment of a subsequent call, the sequence switch contact 454 being closed, the busy lamp 105 adjacent 85 to the jack 104 is lighted indicating to the operator that the trunk line connected to such jack and the group selector associated therewith are not available for use. Multiples of the busy lamp 105 and the circuit 90 therefor may be associated with multiples of the jack 104 if such are used and since the sequence switch contact 454 is closed at all times from the time that a plug is inserted in the jack 104, until the group 95 selector apparatus is again in normal condition, the use of the trunk line leading to such group selector at one of the multiple jacks 104 will cause the lamp 105 to be lighted before all of the other multiples of 100 the jack 104 so that such jack will not be taken for use by any other operator.

Assuming that the desired subscriber has been found busy, information with regard to which has been given to the operator by 101 the flashing of the lamp 118 as has been hereinbefore described, such operator will restore the connection as extended by removing the plug 103 from the jack 104. The restoration of the group selector on 110 Fig. 4 will take place precisely as has been described as a result of disconnection after a call. At this time the sequence switch 551 is in its tenth position. The deenergization of the relay 501 consequent upon the 111 opening of the sequence switch contacts 459 and 456 drives the sequence switch 551 into its eleventh position, over the circuit including sequence switch contact 557 bottom. The brush carriage is now restored 120 to normal in the usual manner followed by the restoration of the sequence switch 551 to its first or normal position.

It should be noted that when the final selector shown in Fig. 5 is utilized for the 121 extension of a call from an exchange of the ordinary local network, such final selector apparatus will operate in precisely the manner described in connection with the extension of a toll call, except that since the 130

relay 514 will not be energized, for reasons which will hereinafter be described, the ringing to the desired subscriber takes place automatically from the source 516 when the 5 sequence switch 551 comes into its twelfth position and the sequence switch contacts 568 bottom and 569 top are closed. When the desired subscriber responds under this source the ringing cutoff relay energized by 10 the increased flow of current due to the closure of the circuit through the subscriber's telephone set, by the attraction of its armature drives the sequence switch 551 out of its twelfth position over a circuit 15 including the sequence switch contact 570 and into its thirteenth or talking position. The other operations of the final selector when used in a local call are well understood and need not be herein described.

20 Should the operator withdraw the plug 103 from the jack 104 in order to break down the connection so far as it may have been established before the key 102 had been released by the energization of the 25 magnet 120, such key may be released thereafter by any preferred mechanical means. It is assumed that this key is of any of the well known types wherein the key when depressed is held in such de- 30 pressed position by a mechanical latch plate which may be either released electrically as by the magnet 120 or by a restoring button of any preferred form. In the case of a release under these conditions the restoration 35 of the key 102 opens a circuit for the relay 202 and consequently, as has been hereinbefore described, such relays of the operator's equipment as are now energized will be deenergized and the circuits for 40 such equipment restored to their normal condition.

If, when upon the completion of the second selection which takes place in the group selector shown in Fig. 4, no one of the trunk 45 lines appearing in the selected sub-group of trunk lines is found idle, the brushes 408, 409 and 410 of this group selector will continue in motion until they come in contact with the busy back terminals 411, 412, 413 50 associated with such sub-group of trunk lines. The busy back apparatus shown connected to such terminals may be common to any desired number of switches and sub-groups therein, such busy back apparatus 55 serving a double function, first, to initiate and produce the proper restoration of the operator's controlling equipment to normal by causing such equipment to pass through its cycle of operations as quickly as possible, 60 consistent with the proper operation thereof, and second, to cause the operation of the supervisory signal before the operator in such a manner as to indicate to her that the call has not been extended beyond the group 65 selector. When the brush 410 of the group

selector comes in contact with the terminal 413 of the busy back the relays 406 and 407 will be energized as the resistances 418 and 419 and the resistance of the windings of the relay 420 are adjusted to allow sufficient current to pass to energize the marginal relay 406 and subsequently thereto the relay 407. The brush carriage of the group selector is, therefore, stopped with the brushes 408, 409 and 410 in contact with the terminals 411, 412, 413 and the sequence switch 451 is driven into its twelfth position. At the same time when the test relays were energized the relay 420 was energized to short circuit its high resistance winding and the resistance 418, so that in spite of the fact that a circuit exists to ground from the test terminal 413 through the relays 406 and 407, the potential of such terminal will be sufficient to energize the relays 406 and 407 of 80 some other group selector the brushes of which, having found no trunk line idle in the selected sub-group of trunk lines, have passed on to the terminals of the busy back. The sequence switch 451 now being in its 85 twelfth position the interrupters 416, 417 will intermittently connect battery and ground to the ring contact of the jack 104 through the resistance 414, 415 respectively. So long as the operator's equipment is associated with the cord 101 and the trunk lines leading to the group selector shown on Fig. 4 the connection to ground through the interrupter 417 is without effect, but the intermittent connection of the battery will 90 cause the counting relays to operate in the well known manner until the relays 308 and 309 have operated, when the usual change-over takes place and such counting relays will again operate due to such intermittent 95 connection to battery until upon the energization of the relays 308 and 309, a second time the equipment is restored to normal and the assignment key released in the manner hereinbefore described with relation to 100 the establishment of a normal connection. As soon as such release has taken place the intermittent connection of the battery will be without effect but the intermittent connection to ground through the interrupter 110 417 will cause the intermittent operation of the relay 122 thereby causing the lamp 118 to flash in accordance with the operation of such interrupter 417, thereby indicating to the operator that an idle trunk line to a desired final selector is not available. Under these circumstances the operator may restore the connection so far as it has been extended by the withdrawal of the plug 103 from the 115 jack 104 and the group selector shown on Fig. 4, and its associated apparatus will be restored as has been hereinbefore described.

Should the desired line be found idle and the subscriber thereat fail to respond, restoration will take place under the control 120 125 130

of the operator precisely as though the called subscriber had responded since in either case the sequence switch 451 is in the twelfth position and the sequence switch 551 5 is in the thirteenth position.

Where it is desired that the trunk line leading from the toll operator's switching section to the group selectors should be of the interoffice or two conductor type the 10 circuits of the trunk line and sub-group selector may be modified as shown in Fig. 6. The relay 601 corresponds in every particular to the relay 401. Upon its initial energization it establishes a circuit to energize 15 the relay 696, which in turn establishes a circuit for lighting the multiple busy lamps 105 and 695 which appears before the multiple jacks 104 and 694. This relay 696 also establishes a circuit for the relay 698. Both 20 the relays 696 and 698 are arranged to release slowly in any preferred manner. It will be recalled that at the initiation of the operation of the operator's controlling equipment the relay 201 was energized and 25 caused the deenergization of the relay 401. Correspondingly the deenergization of the relay 601 is produced and closes at its back contact the circuit for the relay 697 which includes the front contact and armature of 30 the relay 698. The relay 697, by its left armature, establishes a locking circuit for itself, which locking circuit will be maintained until the breaking down of the connection in view of the slow release character 35 of the relays 601, 696 and 698 and the relatively brief periods for which the relay 201 is maintained energized. The relay 697 at its right armature also closes the trunk circuit through to the group selector apparatus. 40 It will be understood that the apparatus indicated to the left of the dotted line in Fig. 6 is located at the toll operator's switching exchange whereas that shown to the right of the dotted line is located at a distant 45 exchange to which it is desired the two wire trunk shall extend. Immediately that the relay 697 has been energized, which as may be noted is coincident with the completion of the fundamental circuit at the 50 operator's controlling equipment, a circuit will be established including the relay 602, sequence switch 655 bottom and the sequence switch 654 top, completing such fundamental circuit at the group selector and causing 55 the energization of the line relay 602 and the stepping relay 213 in the well-known manner. The operation of the group selector on Fig. 6 to select the main group, that is, the bank or level, and the subgroup therein, now 60 takes place in the well-known manner. The relay 602 by energizing closes a circuit over sequence switch contact 653 to drive the sequence switch 651 into its second position. In the second position the sequence switch 65 contact 656 being closed the tripping spin-

dle power magnet 605 receives current and the tripping spindle moves, producing the usual revertive impulses by its interrupter over the sequence switch contact 657 bottom. Upon the completion of the first selection in 70 the group selector the relay 602 deenergizes and the sequence switch 651 is driven out of its second position over a circuit including the sequence switch contact 653. Before the sequence switch 651 reaches its fifth position 75 the fundamental circuit will be again completed at the operator's equipment and the relay 602 being energized, the power magnet 603 of the brush carriage will be energized to move such brush carriage by a 80 circuit including the sequence switch contact 658 bottom. During such movement of the brush carriage impulses are produced in the fundamental circuit by the interrupter 85 621 over the sequence switch contact 657 bottom. On the opening of the fundamental circuit, the brush carriage will be stopped and the sequence switch driven into its seventh position over the back contact of the relay 602 and the sequence switch contact 90 653 top. In this position the first trunk line of the sub-group is tested in the usual manner by the relays 606 and 607 over circuits including the sequence switch contacts 661 and 660 and such line will be 95 seized if it is idle, otherwise, the brush carriage will be further moved by the energization of the power magnet 603 over a circuit including the sequence switch contact 663 and the back contact and armature of 10 the relay 607. If none of the trunk lines of the subgroups are idle the brushes will pass on to the busy back terminals as shown in Fig. 4. Otherwise, upon the seizure of the idle trunk line in the sub-group selected 10 the relays 606 and 607 will be energized and the sequence switch 651 will be driven into its tenth position. In the tenth position of the sequence switch the fundamental circuit will be extended over the sequence switch 11 contact 666 top to the brush 608 and over the sequence switch contact 667 bottom to the brush 609 and the fundamental circuit will, therefore, be completed to the final selector where the tens and units selection will take 11 place precisely in the manner hereinbefore described.

This change over from the hundreds selection controlling operation to the tens selection controlling operation in the operator's equipment and from the fundamental circuit as extended to the line relay 602 at the group selector to the line relay 502 at the final selector involves certain intermediate steps which are rendered desirable due 12 to the particular arrangement of the operator's equipment and to the fact that the relay 213 thereat is designed to operate over both long and short circuits. In the first place since the change over at the oper- 13

ator's controlling equipment takes place in a very short time and may be completed before the group selector has found an idle trunk line to the desired final selector, it is 5 desirable that the fundamental circuit should be closed at the group selector from the time that it is again closed at the operator's equipment until it is completely extended through to the line relay 502 at the 0 final selector, so that the stepping relay 213 may not be falsely operated due to the changing circuits and thereby cause an improper selection. Furthermore, as the line 5 between the selectors may be of varying length it is desirable that precautions should be taken against a false operation of the stepping relay 213 by a sudden change in the self induction of the circuit due to its extension to the line relay 502.

0 To these ends the fundamental circuit, which has been opened at the operator's equipment at the conclusion of the hundreds selection controlling operation, is not opened at the group selector but is maintained through the ninth position by the sequence switch contacts 654 top and 655 bottom. As soon, therefore, as the relay 309 is deenergized at the operator's equipment, the relay 213 is energized over such circuit 0 including the sequence switch contacts 654 top and 655 bottom.

When a free trunk line to the desired final selector has been found and seized the sequence switch 651 is driven into its tenth position as has been described. The relation of the sequence switch contacts 658 top and 667 bottom to the sequence switch contacts 654 top and 655 bottom, is such that both the sequence switch contacts 658 top 5 and 667 bottom are closed before the sequence switch contacts 654 top and 655 bottom are opened. Furthermore, the cams on the sequence switches are so arranged that the sequence switch contact 658 top will close 0 in advance of the sequence switch contact 667 bottom. By this arrangement a circuit is first established for the relay 602 including the resistance 633, the sequence switch contact 658 top and the front contact and armature of the relay 602. The resistance 633 is now in parallel to the stepping relay 213 and while the current through this resistance will be sufficient to maintain the relay 602 energized when the contact 655 bottom opens, it does not sufficiently reduce the current through the relay 213 to cause it to deenergize. The next step is the closure of the sequence switch contact 667 bottom which extends the branch of the fundamental circuit connected to the relay 602 over the low non-inductive resistance 632 and the low resistance winding of the relay 631, in parallel therewith, and the sequence switch contact 667 bottom and brush 609 to the stepping relay 502 at the final selector. It

should be noted that the sequence switch contact 666 top has closed at the same time as the sequence switch contact 667 bottom. When now the sequence switch contacts 654 top and 655 bottom open the flow of current over the fundamental circuit as extended to the final selector has so far increased that the entire current required to energize the stepping relay 213 may flow over the winding of the relay 502 without creating sufficient self-induction therein to cause the armature of the relay 213 to leave its front contact. The relay 602 remains energized over the local circuits traced and the sequence switch 651 remains in its tenth position.

Upon the completion of the units selection at the final selector the sequence switch 551 passes out of its fifth position through its sixth and into its tenth position and 85 from there on in the manner which is hereinbefore described. As the sequence switch 551 left its sixth position the sequence switch contact 571 was opened, so reducing the current in the test circuit of this trunk 90 line that it cannot be seized by any other group selector and that the relay 607 becomes deenergized, it being noted, however, that the relays 606 and 501 remain energized. The deenergization of the relay 95 607 closes a circuit over the sequence switch contact 663 top to drive the sequence switch 651 out of its tenth position and into its fourteenth position. On coming into its eleventh position the sequence switch contact 654 bottom and 655 top are closed extending the trunk line from the operator's position to the repeating coil 629 and such sequence switch contacts are maintained closed through the fourteenth position or 100 talking position of this sequence switch. On coming into the thirteenth position the sequence switch contacts 666 bottom and 667 top are closed and remain closed in the fourteenth position connecting the repeating coil 629 to the trunk line extending to the final selector. While the bridge including the resistance 518 exists across the trunk line at the final selector, the supervisory relay 626 is energized, thereby short circuiting 110 the high resistance winding of the relay 627 and thereby permitting the supervisory relay 122 to energize precisely as such relay was energized directly by the establishment 115 of the bridge including the resistance 518, 120 in the connection as described in connection with Figs. 4 and 5, and with precisely the same results. The ringing in a connection 125 in which a trunk circuit and group selector, as shown in Fig. 6 are utilized takes place from the group selector but is controlled by the key 124 as is standard practice in switching systems of this character. At the time when ringing takes place the relay 626 is deenergized since the sequence switch 551 is in 130

its thirteenth position and the circuit for the direct current is opened at the desired subscriber's sub-station. When the operator depresses the ringing key 124 ringing current passes over the trunk line through the left-hand side of the repeating coil 629 and energizes the relay 628 which is made responsive to such ringing current and rendered opaque to direct current by the condenser 630. The energization of the relay 628 causes the energization of the relay 623, which, at its right armature and front contact connects ringing current to the trunk line extending to the final selector and thence to the desired subscriber's sub-station and at its left armature and front contact connects the other side of such trunk line through the back contact and right armature of the relay 624 and the sequence switch contact 665 to ground. As soon after the called subscriber answers as the operator releases the ringing key 124, which she is periodically depressing in the process of ringing the called line, relay 628 deenergizes to in turn cause the deenergization of relay 623. The called line being now closed at the substation, supervisory relay 626 energizes over a circuit including the called line and the back contacts and armatures of relay 623. Relay 626, upon energizing, short-circuits the right-hand high resistance winding of relay 627, thus reducing the resistance in series with relay 122 at the operator's position. Relay 122 now operates to display, in the manner above described, the supervisory signal before the operator.

It is desirable that the trunk line leading to the group selector on Fig. 6 should be available for a subsequent call as promptly as possible after the initiation of restoration of an established call by the withdrawal of a plug 103 from a jack 104. It is, therefore, desirable that an operator may insert the plug 103 of some other cord circuit or of the same cord circuit for a subsequent call into one of the jacks 104 or 694 immediately that such restoration has been initiated, without holding up the restoration of the apparatus or preventing the proper establishment of the new call. It may be that the trunk line is taken for use again immediately it is made free by the removal of the plug from the jack, breaking down the previous connection. Some time, of course, will elapse before the operator, having inserted the plug, has depressed the assignment key and the number keys. It may be, however, that this is completed before the switch carriage of the group selector has returned to its normal position. In this event the premature closure of the fundamental circuit by the relay 697 might result detrimentally and therefore, the fundamental circuit is kept prepared during the restoration of the group selector apparatus by the closure in the

fifteenth to eighteenth positions of the sequence switch 651 of the sequence switch contact 654 top and the sequence switch contact 664 top, the fundamental circuit under these conditions including at the group selector the left winding of the relay 624. The sequence switch contact 655 bottom is arranged to close before the sequence switch contact 664 top opens. The premature completion of the fundamental circuit at the operator's equipment and by the relay 697 will, therefore, be without detrimental effect as the stepping relay 213 is maintained energized continuously over the left winding of the relay 624 during the restoration of the sequence switch 651 and the brush carriage of the group selector to normal, and over the branch of the fundamental circuit through the relay 602 thereafter.

The relay 624 is also utilized to prevent the disturbance of conversations already existing on trunk lines leading to final selectors over which the brushes of the group selectors must pass if disconnection is made prematurely, while the group selector is searching for an idle trunk line to a final selector. In this event the relay 602 will be deenergized as the sequence switch 651 reaches its ninth position and a circuit is therefore established over the sequence switch contact 664 bottom to energize the relay 624 which, by locking up over its right winding, front contact and right armature and sequence switch contact 665, energizes the relay 623, opening the circuit from the repeating coil to the brushes 608 and 609, the prevention of the impressing of ringing current on the trunk lines being accomplished by the attraction of the left armature of the relay 624 which opens the circuit from the source of ringing current, the ground which would otherwise be connected to the brush 609 being disconnected at the back contact and right armature of the relay 624. In case the group selector shown on Fig. 6 should not find an idle trunk line in the selected sub-group of trunk lines the brushes 608, 609 and 610 thereof will pass on to the usual busy back terminals as shown in and described in connection with Fig. 4. It is desirable that the release of the test relays of the group selector should be initiated, under these circumstances, locally. For this purpose the low resistance winding of the relay 631 is included in the fundamental circuit as it would be extended to the brush 609 in parallel to the low resistance non-inductive resistance 632. Insufficient current would flow in the fundamental circuit while such fundamental circuit includes the stepping relay 213 to energize the relay 631. When, however, the fundamental circuit has been broken down at the operator's equipment in response to the continued sending of battery impulses from the busy back and

the supervisory relay 122 is included in substitution therefor the relay 631 will energize, opening the circuit of the test relay 607 and locking itself up through the sixteenth position of the sequence switch 651 over the sequence switch contact 660. The retraction of the armature of the relay 607 closes a circuit over the sequence switch contact 663 top to drive the sequence switch 651 out of its tenth position and into its fourteenth position, from which position the apparatus of the group selector and the switch carriage thereat may be restored to normal by the withdrawal of the plug 103 from the jack 104 or 694 in the hereinbefore described manner.

Fig. 7 illustrates diagrammatically an exchange system embodying the present invention. The circuits and apparatus indicated above and to one side of the dotted line illustrate a usual automatic or semi-automatic telephone exchange system of from 10,000 to 20,000 lines. The circuits and apparatus shown on the other side of the dotted line illustrate the special toll switching apparatus and its relation to the apparatus of the ordinary exchange. In the ordinary exchange as illustrated in this figure a line from the sub-station 11, when calling is extended over the usual first line finder switch 12 to the terminals of the second line finders 13 by one of which such line is further extended to a connecting circuit 14. When so extended the connecting circuit taken for use is, in any preferred manner, associated with the registering and controlling equipment 15, which may be either adapted for receiving impulses from the sub-station and thereafter controlling the selection of the desired line or may be a semi-automatic operator's registering and controlling equipment in which the desired number is recorded upon numerical keys in any preferred form and arrangement, and the selection controlling operations are performed in accordance with such recordation. Under the control of the registering and controlling equipment 15, the call is extended over a first group selector 16 to a trunk line of the number group appearing on a bank or level thereof leading to a second group selector 17, where again, under the control of the equipment 15, a number group of trunk lines located on a bank or level of the second group selector 17 is selected and an idle trunk line in such group leading to a final selector 18, which final selector has access to and selects, under the control of the equipment 15, the particular terminals of the desired line in the well known manner.

In the toll exchange forming a part of the general circuit shown, the toll or junction lines 20 are connected to the connecting circuit or cords 101 in any preferred manner, as shown by means of plugs and jacks.

The toll operator by the assignment key 102 associates the cord taken for use with the toll registering and controlling equipment as has been hereinbefore described and by inserting the plug 103 in the jack 104 extends the circuit from the cord circuit 101 to the toll group selector 19. This group selector, the circuits of which are shown in detail on Fig. 4, selects first a large group, that is a bank or level, and subsequently a sub-group in such large group leading to the particular group of final selectors of the ordinary or local exchange in which the desired line is to be found.

The final selectors to which the toll group selector 19 has access may be used for ordinary local calls as indicated, but the trunk lines leading to such final selectors to which the toll group selector 19 has access are so located on the multiples of the group selectors 17 that they will only be selected by such group selectors 17 if all of the other trunk lines leading to the particular group of final selectors are busy. These final selectors serving for both local and toll calls are indicated at 18^a. Associated with each of such final selectors 18^a is the relay 514 (see Fig. 5) which serves to prevent the ringing of the called subscriber by the usual automatic ringing apparatus associated with the final selectors.

The operation of this relay 514 is based in the particular system illustrated on the arrangement that in the ordinary or local exchange the battery used and connected in the repeating coils of the cord circuits 14 is a 24 volt battery, such battery being also connected to the relay 514. When a call is extended through the local exchange to one of the final selectors 18^a the relay 514, since it is connected on both sides thereof to a 24 volt battery will not be energized and the ringing of the called subscriber will take place in the usual way. It is standard practice that the ringing of the called subscriber when a toll connection is extended thereto should be under the control of a toll operator for reasons which need not be gone into herein. On the toll switching section the battery utilized is the 48 volt battery and such battery is included in the repeating coils of the cord circuits 101. When, therefore, a circuit is extended to one of the final selectors 18^a from the toll switching section, current at 24 volts will pass through the relay 514 (see Figs. 1, 4 and 5) and such relay will be energized causing the sequence switch of such final selector to pass through the ringing position without ringing current being applied to the desired line as has hereinbefore been described. It will, therefore, be seen that by the use of special group selectors 19 and the arrangements for controlling the relay 514 as described, toll service embodying the usual special features

which are desirable may be performed in connection with a usual local exchange and to work with a minimum of special apparatus and with a minimum of apparatus 5 maintained busy during the extension of a toll call. It will be obvious that to increase the capacity of the local exchange network to 200,000 lines it will be necessary only to add third group selectors operating in a 10 manner precisely similar to the usual first and second group selectors 16, 17 shown. To provide for this additional selection in the toll switching system either a set of ordinary group selectors may be inserted between the jacks 104 and the several sets of 15 selectors 19 or the first selection may be accomplished by the operator in selecting a jack 104 connected to a trunk line leading to a selector 19 of the desired group. Further increase in capacity may be accomplished by the use of further series of group 20 selectors the registering and controlling equipments of both the local and toll switching systems being adapted in the obvious 25 manner to control the necessary additional selections.

What I claim is:—

1. In a telephone exchange system, telephone lines, an operator's position, a connecting circuit at said position, means for extending said lines to said connecting circuit, automatic switches for further extending said lines, a registering and controlling equipment under the control of said operator 30 for controlling said switches, a trunk line leading to said switches, an assignment key individual to said connecting circuit for associating said equipment therewith, and a plug and jack switch for connecting said 35 connecting circuit to said trunk, the insertion of said plug in the jack serving jointly with the operation of said assignment key to associate the registering equipment with said connecting circuit:

2. In a telephone exchange system, telephone lines, an operator's position, a connecting circuit at said position, means for extending said lines to said connecting circuit, automatic switches for further extending said lines, a registering equipment for controlling said automatic switches, a trunk line leading to said switches, an assignment key individual to said connecting circuit for associating said equipment therewith, a plug 50 and jack switch for connecting said connecting circuit to said trunk, the insertion of said plug in the jack serving jointly with the operation of the assignment key to associate the registering equipment with said connecting circuit, and means for disassociating said equipment from the connecting circuit either after the completion of its controlling operation or in response to the removal of said plug from the jack.

3. In a telephone exchange system, tele-

phone lines, an operator's position, a connecting circuit at said position, means for extending said lines to said connecting circuit, automatic switches for further extending said lines, a register equipment for controlling said automatic switches, a trunk line leading to said switches, an assignment key individual to said connecting circuit for associating said equipment therewith, a plug and jack switch for connecting said connecting circuit to said trunk, the insertion of said plug in the jack serving jointly with the operation of the assignment key to associate the register equipment with said connecting circuit, means for disassociating said equipment from the connecting circuit after the completion of its controlling operation, and means for disassociating said equipment from the connecting circuit in response to the removal of said plug from the jack irrespective of the condition said equipment is in when said plug is removed.

4. In a telephone exchange system, a calling line, a called line, an operator's position, automatic switches, a trunk line leading from said position to the automatic switches, a register controlling equipment at the operator's position for controlling said switches, means for connecting the calling line to said trunk at the operator's position, means for establishing a control circuit including said trunk from the register equipment to the automatic switches for controlling said switches to further extend the calling line to the called line, and a busy signal at the operator's position, operated as soon as the calling line is connected to said trunk independent of the completion of said control circuit.

5. In a telephone exchange system, a calling line, a called line, an operator's position, automatic switches, a trunk line leading from the operator's position to said switches, a register controlling equipment at the operator's position for controlling said switches, a plug and jack for connecting the calling line to said trunk at the operator's position, means for establishing a control circuit including said trunk from the register equipment to the automatic switches for controlling said switches to further extend the calling line to the called line, and a busy signal at the operator's position operative as soon as the calling line is connected to said trunk independent of the completion of said control circuit.

6. In a telephone exchange system, a calling line, a called line, an operator's position, automatic switches, a two-conductor trunk line leading from said position to said switches, a register controlling equipment at the operator's position for controlling said switches, means for connecting the calling line to said trunk at the operator's position, means for establishing a control circuit in-

cluding said trunk line from the register equipment to the automatic switches for controlling said switches to further extend the calling line to the called line, and a busy signal at the operator's position operated as soon as the calling line is connected to said trunk independent of the completion of said control circuit.

7. In a telephone exchange system, a calling line, a called line, an operator's position, automatic switches, a two conductor trunk line leading from the operator's position to said switches, a register controlling equipment at the operator's position for controlling said switches, means for connecting the calling line to said trunk, means for establishing a control circuit including said trunk from said registering equipment to the automatic switches for controlling said switches to further extend the calling line to said called line, a busy signal at the operator's position, and a relay for causing the operation of said signal upon the connection of the calling line to said trunk, said relay being arranged to control the closure of said control circuit by a subsequent operation.

8. In a telephone exchange system, an exchange, subscribers' lines incoming to said exchange, toll lines incoming to said exchange, a group of final selectors for extending connections, a group of trunks, a group selector for extending said subscriber's line over said trunks to said final selectors, a second group of trunks, and a special group selector for extending said toll lines over said second group of trunks to the final selectors, said trunk groups being arranged such that all the final selectors of said group are available for extending said subscribers' lines while only a portion of said group of final selectors is available for extending said toll lines.

9. In a telephone exchange system, an exchange, subscribers' lines incoming to said exchange, toll lines incoming to said exchange, a group of final selectors for extending connections, a group of trunks, a group selector for extending said subscribers' lines over said trunks to said final selectors, said group selector being arranged to perform a single numerical selection, a second group of trunks, and a special group selector for extending said toll lines over said second group of trunks to the final selectors, said special group selector being arranged to perform two numerical selections, said trunk groups being arranged such that all the final selectors of said group are available for extending said subscribers' lines while only a portion of said group of final selectors are available for extending said toll lines.

10. In a telephone exchange system, tele-

phone lines, a group of trunks, selector switches for connecting said lines to said trunks, a register controlling equipment for controlling the operation of said switches, a restoring mechanism, a circuit for said mechanism appearing in multiples of said switches, said switches being arranged to associate said register equipment with said restoring mechanism when all said trunks are busy, means operated by said restoring mechanism for restoring said register equipment to normal, and means for rendering said restoring mechanism selectable simultaneously by a plurality of said selector switches.

11. In a telephone exchange system, telephone lines, automatic switches for extending said lines, a registering and controlling equipment including a set of counting relays for controlling the selective operations of said switches, means for energizing said relays during the selective operations, a locking circuit for maintaining said relays energized, and means for gradually reducing and interrupting the flow of current in said circuit.

12. In a telephone exchange system, telephone lines, automatic switches for extending said lines, a registering and controlling equipment including a set of counting relays for controlling the selective operations of said switches, means for energizing said relays during the selective operations, a locking circuit for maintaining said relays energized, and means for gradually reducing and interrupting the flow of current in said circuit at the termination of each successive selective operation.

13. In a telephone exchange system, subscribers' lines, toll lines, a called line, an automatic selective switch in which said called line appears, means for extending said subscribers' lines to said switch, means for extending said toll lines to said switch, means for operating said switch to connect either said subscribers' lines or said toll lines to the called line, means associated with said switch for applying ringing current to the called line when one of said subscribers' lines is connected therewith and for withholding such ringing current when a toll line is extended to the called line, and manual means for sending ringing current over the called line when a toll line is connected thereto.

14. In a telephone exchange system, subscribers' lines, toll lines, a called line, an automatic selector switch in which said called line appears, means for extending said subscribers' lines to said switch, means for extending said toll lines to said switch, means for operating said switch to connect either said subscribers' lines or said toll lines to the called line, an operator's posi-

tion, means associated with said switch for applying ringing current to the called line when one of said subscribers' lines is connected therewith, means controlled from 5 said position when a toll line is connected to said called line for withholding the application of ringing current, and manual

means under the control of the operator for sending ringing current over the called line.

In witness whereof I hereunto subscribe 10 my name this 20th day of February A. D., 1918.

LIPA POLINKOWSKY.
